UNITED STATES PATENT OFFICE.

JOHN NELSON, OF NEWTON, IOWA.

GEARING FOR WASHING-MACHINES.

1,307,101.

Specification of Letters Patent. Patented June 17, 1919.

Application filed October 22, 1917. Serial No. 197,971.

To all whom it may concern:

Be it known that I, JOHN NELSON, a citizen of the United States, residing at Newton, in the county of Jasper and State 5 of Iowa, have invented certain new and useful Improvements in Gearings for Washing-Machines, of which the following is a specification.

The invention relates to an improvement

- 10 in gearing for combined washing and wringing machines of that type designed to be driven by a motor. The gearing of the present invention is designed primarily for use in connection with a washing machine of a
- 15 well known type which includes a frame, a pair of tubs mounted thereon, a rotary agitator or dolly within each tub, and a wringer mechanism mounted above and between the tubs, and it is the primary aim of
- 20 the invention to provide means for rotating the agitators and operating the wringer mechanism embodying a motor and a system of gearing for transmitting power from the motor to the said agitators and wringer
- 25 mechanism embodying control levers so arranged and located that the operator of the machine may manipulate the levers selectively without changing his or her position with relation to the machine whereby to put
- 30 into operation either or both of the agitators or to discontinue the operation of either or both of the agitators and set in operation the wringer mechanism. In certain types of such machines there has been provided an
- 35 arrangement of gearing in which the controlling levers have been positioned at various points about the machine rendering it necessary for the operator to walk around the machine in order to properly control
- 40 the operation thereof and it will be understood from the foregoing that the primary object of the present invention is to overcome the disadvantages resulting from such an inconvenient arrangement of the said
- 45 levers.

The invention also aims to provide an arrangement of gearing which will be extremely simple and not in any way liable to get out of order and by which a more direct 50 drive and economy in expenditure of power is provided for.

In the accompanying drawings:

Figure 1 is a side elevation of the gearing embodying the present invention, the washing and wringing mechanism to be operated

through the gearing being illustrated in dotted lines so as to illustrate the application of the invention;

Fig. 2 is a perspective view of the gearing embodying the present invention; 60

Fig. 3 is a top plan view of the gearing;

Fig. 4 is a vertical longitudinal sectional view taken substantially on the line 4—4 of Fig. 3;

Fig. 5 is a detail view in elevation illustrating one of the bearings for the rods which are adjustable to control the shiftable elements of the gearing. 65

In the drawings, the supporting frame structure of the combined washing and wringing machine is indicated in general by the numeral 1 and the numerals 2 and 3 indicate tubs which are mounted upon this frame. The agitator shafts arranged within the tubs 2 and 3 and mounted in bearings 70 in the tops of the said tubs are indicated respectively by the numerals 4 and 5. The wringer mechanism is indicated in general by the numeral 6 and the shaft which transmits motion to the said mechanism is 75 indicated by the numeral 7 and is mounted in a tubular standard 8 supported within the frame 1 and extending upwardly between and at one side of the tubs 2 and 3. Inasmuch as the present invention is not concerned with any specific form of agitator or dolly nor with any specific wringer mechanism, these parts of the washing and wringing machine will not be specifically described. 80 In fact, the shafts 4 and 5 may serve to rotate or oscillate any desired form of agitator and the shaft 7 may transmit motion to any desired form of wringer mechanism, the invention residing, on the other hand, in gearing through the medium of 85 which power may be transmitted independently to these parts in unison or selectively.

Supported within the frame 1 are spaced platforms 9 and 10 and mounted upon the platform 9 is an electric or other suitable 100 motor 11, the shaft of which is indicated by the numeral 12 and has fixed upon it a pinion 13, said pinion 13 meshing with a gear 14 of relatively large diameter which is fixed upon one end of a shaft 15. This shaft 15 at 105 its said end is journaled in a bearing 16 upon the platform 9 and near its other end is journaled in a bearing 17 mounted upon the platform 10. Inasmuch as the gear 14 is fixed upon the shaft 15, when the motor 110

11 is in operation power will be transmitted continuously to the said shaft 15. A pinion 18 is loosely mounted upon the shaft 15 beside the gear 14 and meshes with a gear 19 mounted upon a stub shaft 20. In order that this pinion 18 may be clutched with the shaft 15 for rotation therewith, there is slidably keyed upon the said shaft 15 beside the said pinion a clutch element 21, the adjacent ends of the hubs of the pinion 18 and clutch member 21 being provided respectively with clutch teeth 22 and 23 which will mutually engage each other when the member 21 is shifted toward the pinion 18. In order that the clutch member 21 may be shifted, as stated, an arm 24 is provided at its lower end with a yoke 25 engaging a peripheral groove 26 in the said member and this arm is supported from a rod 27 which is slidably mounted through an opening 28 formed in the depending wing of a bracket member 29 which may either constitute an integral portion of the frame 1, which frame is formed from angle iron bars, or may be in the nature of a separate length of angle iron secured to one of the side members of the frame. The horizontal wing of this bracket is indicated by the numeral 30 and fitted through the said wing near the ends thereof are bolts 31 which extend also through openings in a plate 32 supported by the bolts in spaced relation to the under side of the said wing 30. Springs 33 are fitted upon the bolts and bear at their upper ends against the under side of the plate 32 and may be tensioned by adjusting nuts 34 which are threaded on to the lower ends of the bolts. The upper side of the plate 32 bears frictionally against the under side of the rod 27 and other similar rods which will be presently described and serves to hold the rod and the other rods mentioned against displacement after having been shifted to the desired position of adjustment. The outer end of this rod 27 is provided with an upstanding hand grip 35 which may be grasped for the purpose of shifting the rod and it will be observed by reference to Fig. 3 of the drawings that this hand grip is located at one side of the machine as well as the hand grips for the other rods mentioned. The inner end of the rod 27 is slidably fitted through an opening in a bracket or bearing member 36 mounted at any convenient point within the frame 1 to support the inner end of the rod and prevent sagging of the rod. A pinion 37 is loosely mounted upon the shaft 15 and has a clutch portion 38 for co-operation with a clutch member 39 corresponding in construction to the clutch member 21. The clutch member 39 is shifted through the medium of an arm 40 which corresponds to the arm 24 and which depends from a rod 41 mounted in another opening formed in the bracket 29 and is supported at its inner end and guided by means of the bracket 36. The rod 41 is provided at its outer end with a hand grip 42 which preferably extends in the same direction as the hand grip 35 and these hand grips are spaced a short distance apart and are, of course, both located at the same side of the machine so that either may be conveniently grasped without the operator changing his or her position. The pinion 37 meshes with a gear 43 mounted upon a stub shaft 44, the shaft being supported in a suitable bearing upon the platform 10. Connected by means of crank pins to the gears 19 and 43 are pitmen 45 and 46, respectively, and these pitmen are pivotally connected at their outer ends to the lower ends of rock levers 47 to the upper ends of which levers are connected the outer ends of rack bars 48. The inner ends of these bars are of rack formation, as indicated at 49, and mesh with pinions (not shown) at the upper ends of the shafts 4 and 5. At this point it will be understood that the shaft 15 being driven from the motor, either or both of the agitator shafts 4 and 5 may be set in operation by adjusting the rods 27 and 41. For example, when it is desired that the shaft 5 alone shall be rotated the rod 41 is shifted so as to bring the clutch member 39 into clutch with the pinion 37, and, on the other hand, when it is desired that the shaft 4 shall be rotated the rod 27 is correspondingly adjusted so as to bring the clutch member 21 into engagement with the pinion 18. Of course, either or both of the shafts 4 and 5 may be rendered active or inactive while the motor is running.

A sprocket gear 50 is also loosely mounted upon the shaft 15 and trained thereover and over a sprocket 51 upon a shaft 52 is a sprocket chain 53. The shaft 52 is mounted in a suitable bearing bracket 54 within the frame 1 and has fixed upon it a bevel pinion meshing with a similar pinion 55 fixed at the lower end of the shaft 7. A clutch member 56 is slidably keyed upon the shaft 15 and the said clutch member and sprocket gear 50 have co-operating clutch portions 57 which coact to clutch the gear 50 with the shaft 15 when the clutch member 56 is shifted toward the said gear. An arm 58 corresponding to the arms 24 and 40 is associated with the clutch member 56 to provide for shifting thereof and this arm extends downwardly from a rod 59 which is located between the rods 27 and 41 and slidably mounted in the brackets or bearings 29 and 36 and an additional bearing 60. The rod 59 is provided at its outer end with a hand grip 61 which preferably extends downwardly, or in any event, in a direction different from the direction in which the hand grips 35 and 42

extend. By reason of this arrangement of the hand grips confusion is avoided when the rods 27, 41 and 59 are to be adjusted for the operator is aware of the fact that the 5 grips 49 and 32 for controlling the agitator shafts for the two tubs extend in one direction while the hand grip for controlling the wringer mechanism extends in the opposite direction.

10 Having thus described the invention, what is claimed as new is:

1. In mechanism of the class described, a driven shaft, a plurality of clutch members on said shaft, rods extending parallel to the 15 shaft and slidably mounted side by side, and arms extending from the rods and each engaging one of the clutch members, the said rods being provided with handle portions located in relatively close proximity to each 20 other, the handle portions being turned at angles to their respective rods and one handle portion extending in an opposite direction to another.

2. In mechanism of the class described, a 25 driven shaft, a plurality of clutch members upon the shaft, rods having operative connection with the respective clutch members and independently shiftable to independently shift the clutch members, a bearing 30 for the rods, having openings through which the rods are slidably fitted, and a friction member mounted upon the bearing and en-

gaging the said rods whereby to frictionally hold the same in adjusted position.

3. In mechanism of the class described, a 35 driven shaft, a plurality of clutch members upon the shaft, rods having operative connection with the respective clutch members and independently shiftable to independently shift the clutch members, a bearing 40 for the rods having openings through which the rods are slidably fitted, a plate disposed to extend transversely of the rods and with one side frictionally engaging the rods, and means yieldably holding the plate in such 45 engagement.

4. In mechanism of the class described, a driven shaft, a plurality of clutch members mounted thereon and each arranged to lock a gear thereto, a plurality of rods mounted 50 parallel to the shaft and to each other, arms extending from the respective rods and engaging the respective clutch members, the said rods being arranged side by side, handle members extending angularly in a common 55 direction from the outer of said rods, and a handle member extending angularly in the opposite direction from a rod intermediate said outer rods, the said handle members being located in relatively close proximity 60 to each other.

In testimony whereof I affix my signature.

JOHN NELSON. [L.S.]
